US00D555661S

(12) United States Design Patent (10) Patent No.: US D555,661 S
Kim (45) Date of Patent: * Nov. 20, 2007

(54) MOBILE PHONE DISPLAY PANEL WITH MENUS

(75) Inventor: Jun-Seek Kim, Seoul (KR)

(73) Assignee: Samsung Electronics Co., Ltd., Suwon-Si (KR)

() Term: 14 Years

(21) Appl. No.: 29/241,327

(22) Filed: Oct. 27, 2005

(30) Foreign Application Priority Data

Apr. 27, 2005 (KR) 30-2005-0014136

(51) LOC (8) Cl. 14-04

(52) U.S. Cl. D14/486

(58) Field of Classification Search D14/485-495; 715/512, 700, 716, 717, 718, 719, 720, 721, 715/722, 723, 762, 763, 764, 768, 771, 779, 715/780, 781, 783, 784, 787, 803, 808, 809, 715/810, 816, 819, 820, 821, 822, 823, 824, 715/825, 828, 829, 841, 842, 843, 845, 864, 715/867, 900, 901, 902, 906, 908, 909, 910, 715/961, 962, 975; 345/689, 902

See application file for complete search history.

(57) CLAIM

The ornamental design for the mobile phone display panel with menus, as shown and described.

DESCRIPTION

The sole FIGURE is a front view of the mobile phone display panel with menus showing my design.

The broken line in the FIGURE is included for the purpose of illustrating a display panel and forms no part of the claimed design.

1 Claim, 1 Drawing Sheet
